UNITED STATES PATENT OFFICE.

ARTHUR SUTTON, OF CHICAGO, ILLINOIS, ASSIGNOR TO CHICAGO WOOD FINISHING CO., OF CHICAGO, ILLINOIS, A CORPORATION OF ILLINOIS.

MACHINE FOR PRINTING A REPRODUCTION OF THE GRAIN OF WOOD.

No. 869,148.

Specification of Letters Patent.

Patented Oct. 22, 1907.

Application filed May 16, 1907. Serial No. 373,974.

To all whom it may concern:

Be it known that I, ARTHUR SUTTON, a citizen of the United States, residing at Chicago, in the county of Cook and State of Illinois, have invented new and useful Improvements in Machines for Printing a Reproduction of the Grain of Wood, of which the following is a specification.

The object of this invention is to provide a machine of simple construction and easily operable for printing 10 on one board, such as a plain sawed board, the grain design of another board, such as a quarter sawed board, so that the board on which the design has been printed will, after it has been varnished and polished, present the appearance of the board from which the design has 15 been taken.

In the accompanying drawings illustrating one embodiment of the invention Figure 1 is an elevation of part of the machine showing the carriage which carries the board in initial position and omitting the left hand 20 end of the frame. Fig. 2 is a similar view showing the carriage in its forward position and omitting the right hand end of the frame. Fig. 3 is an enlarged view of the central part of the machine showing the principal working parts. Fig. 4 is a sectional view looking at 25 Fig. 1 from the left thereof. Fig. 5 is a detail plan view and Fig. 6 is a detail sectional view showing the trough in the carriage. Fig. 7 is a detail view showing a portion of the rack and the pinion. Fig. 8 is a detail sectional elevation of one end of the scraper and its guide. 30 Fig. 9 is a sectional view on the line 9—9 of Fig. 8. Fig. 10 is a top plan view of the left hand end of Fig. 8.

The machine comprises a frame 11 which can be conveniently made of pipe as illustrated in the drawings and of any desired size. A carriage 12 is arranged to 35 travel from end to end of the frame and is provided with grooved wheels 13 which travel on rails 14 supported on the frame. A main shaft 15 is journaled in bearings in the frame and carries a pinion 16 which meshes with a rack 17 on the underside of the carriage, 40 whereby the carriage is moved back and forth in the frame. At or about the middle of the frame, and on each side thereof, are uprights 18 on which the bearing blocks 19 are rigidly mounted and the bearing blocks 20 are slidably mounted. A transfer roller 21 is mounted 45 on a shaft 22 journaled in bearings in said bearing blocks 20 and this shaft carries a bevel gear 23 which meshes with a bevel pinion 24 on an upright shaft 25 which is supported in a bracket 26 on the bearing block 20 and in brackets 27 on the bearing block 19 (Figs. 3, 50 4). The shaft 25 is movable vertically with the movable blocks 20, as hereafter described, and a bevel pin-

ion 28 is fastened on said shaft between the brackets 27 by a feather 29 and meshes with a bevel pinion 30 on the main shaft 15. The bearing blocks 19 and 20 on each side of the machine are connected by toggle links 55 31 which are pivoted together at 32 and at 32' to said blocks.

An ink roller 33 is supported by swinging arms 34 which are loosely mounted on the shaft 22 and this ink roller receives ink from a feed roller 35 which operates 60 in engagement with a roller 36 operating in an ink pot 37. I prefer to make the ink roller 33 like an ordinary printing ink roller, the roller 35 of similar character and the roller 36 of steel.

A benzin roller 38 is carried by a frame 39 mounted in bracket arms 40 on the movable blocks 20 so that it can be swung from the position shown in Fig. 1 with the benzin roller in the tank 41 to the position shown in broken lines in Fig. 3 with the benzin roller resting upon the transfer roller 21. The tank 41 is suitably 70 supported on the main frame of the machine and contains a supply of benzin or other cleaning material, a supply of which is carried by the roller 38 on to the transfer roller for cleaning the latter. A roller 42 is mounted on a shaft 43 carried by arms 39' mounted 75 on shaft 47 and said shaft 43 carries a pinion 44 which meshes with a pinion 45 also mounted on the frame 39. The pinion 45 meshes with a pinion 46 on a shaft 47 supported on the frame 39 and carrying also a sprocket wheel 48. A sprocket chain 49 travels on the sprocket 80 wheel 48 and on a sprocket wheel 50 on the transfer roller shaft 22. Thus the roller 42 is revolved to operate as a scraper on the transfer roller during the cleaning operation.

The main shaft 15 carries a loose pulley 51 and two 85 tight pulleys 52 to receive two belts, one of which 53 is straight and the other 54 is crossed. A belt shifter 55 is suitably engaged with these belts and is carried by an arm 56 pivotally mounted at 57 on one of the movable bearing blocks 20. A link 58 is pivotally connected at 59 to the stationary bearing block 19 and at 60 to the arm 56 (Fig. 4), whereby the belts are shifted on the pulleys to reverse the movement of the carriage as the transfer roller is elevated and lowered.

A scraper blade 61 (Figs. 3, 8, 9, 10) is securely held 95 between plates 62 and 63 bolted together and the latter rest in end guides 64 mounted on the main frame and adjustable longitudinally thereof. The scraper may be variously constructed but I have illustrated it as operating by gravity to engage the master board hereafter referred to. The carriage is provided with tracks 100 65 which slide under the lower ends 34 of the arms 34

and under the plates 62 and 63 of the scraper device between the scraper blade and the end guides 64. These tracks are elevated at 65' at the right hand end of the carriage. A drip pan 66 is provided on the carriage to receive the drippings from the scraper.

In practice the ink pot is provided with a supply of ink and the benzin tank with a supply of benzin and a master board 67, from which the design is taken, is arranged on the table and is alined with a board 68 on which the design is to be printed. The machine is started and the carriage travels to the left (Fig. 1) carrying the master board under the ink roller, the scraper and the transfer roller. The ink roller applies ink to the master board, rolling it into the grain thereof and the scraper resting on the board removes surplus ink from the face of the board so that the transfer roller will receive a transfer in ink of the design of the grain of the master board. As the carriage carries the master board forward from beneath the ink roller the arms 34, carrying said roller, will ride up the inclines 65" on to the elevated tracks 65' so that the ink roller will be held above and out of engagement with the board 68. The scraper likewise rides up on the elevated track 65' and is held out of engagement with the board 68. The carriage then carries the board 68 beneath the transfer roller which prints the design of the grain of the master board thereon. During the movement of the carriage from right to left the transfer roller is in its lowered position (Fig. 1) but as the carriage reaches the limit of its movement from right to left stops 69 on the right hand end of the carriage engage the toggle links and push them from broken position (Fig. 1) to straight position (Fig. 2) thereby raising the bearing blocks 20 and elevating the transfer roller. Thus the belt shifter arm 56 is operated to shift the belt and reverse the direction of movement of the carriage. When the carriage reaches the limit of its movement from left to right stops 70 on the left hand end of the carriage engage the toggle links and move them from the straight position (Fig. 2) to broken position (Fig. 1), thereby lowering the transfer roller into operative position. It will be apparent that the same design may be printed on as many different boards as desired or the master board may be changed as frequently as desired, and that more than one master board may be used at a time, lying side by side on the table. When it is desired to clean the transfer roller the frame 39 is swung from the position shown in Fig. 1 to the position shown in Fig. 2 carrying the benzin roller 38 from the benzin tank 41 into engagement with the transfer roller. The benzin roller applies benzin to the transfer roller so that the ink thereon may be readily wiped off by the roller 42.

The machine is simple in construction and operates easily and without requiring skilled attention. It will print the grain design of one board on another, such as the design of a quarter sawed board on a plain sawed board, or the design of any board having a grain upon a board without a grain, or a grain which is not plain or prominent. Thus a board may be made to imitate and present the appearance of the grain design of another board and by varnishing and polishing properly it can be made practically indistinguishable in appearance from the master board which it represents.

What I claim and desire to secure by Letters Patent is—

1. In a machine of the character described, the combination of a frame, a reciprocating carriage to carry a master board and a board to be printed, said boards being arranged end to end on the carriage with the master board in front, an ink roller for applying ink to the master board, a transfer roller to receive an impression from the master board and apply it to the other board, a scraper between said rollers, and means for automatically moving the ink roller and scraper out of operative position after the master board has passed thereby, substantially as described. 75
2. In a machine of the character described, the combination of a frame, a reciprocating carriage to carry a master board and a board to be printed, said boards being arranged end to end on the carriage with the master board in front, an ink roller for applying ink to the master board, a transfer roller for receiving an impression from the master board and applying it on the other board, a scraper for removing surplus ink from the master board, means for automatically lifting the ink roller and the scraper out of operative position after the master board has passed thereby, and means for lifting the transfer roller out of operative position after it has operated on the board to be printed and before the carriage begins its return movement. 80
3. In a machine of the character described, the combination of a frame, a pair of swinging arms, an ink roller supported on said arms, a transfer roller, a scraper between said rollers, a movable carriage to carry a master board and a board to be printed successively beneath the ink roller, the scraper and the transfer roller, and tracks on said carriage on which the free ends of said arms and the scraper rest, said tracks having inclines and being elevated adjacent to the board to be printed, whereby the ink roller and the scraper are moved out of operative position after they have operated on the master board. 90
4. In a machine of the character described, the combination of a frame, a gravity ink roller, a transfer roller, a gravity scraper between said rollers, a movable carriage to carry a master board and a board to be printed successively beneath the ink roller, the scraper and the transfer roller, and stops at the ends of said carriage, and means operated by said stops to move the transfer roller into and out of operative position. 95
5. In a machine of the character described, the combination of a frame, an ink roller, a scraper, vertically movable bearing blocks on the frame, a transfer roller journaled in said bearing blocks, toggle links pivotally connected to said bearing blocks and to a fixed part of the frame, a movable carriage to carry a master board and a board to be printed successively beneath the ink roller, the 115 scraper and the transfer roller, and stops at each end of the carriage to engage and operate said toggle links. 110
6. In a machine of the character described, the combination of a frame, an ink roller, a scraper, a pair of stationary bearing blocks on the frame, another pair of bearing blocks movable vertically on the frame, a shaft journaled in said movable bearing blocks, a transfer roller on said shaft, a main shaft, an upright shaft carried by one of the movable bearing blocks and geared to said transfer roller shaft and main shaft, toggle links pivotally connected to the stationary bearing blocks and to the movable bearing blocks, a reciprocating carriage to carry a master board and a board to be printed successively beneath the ink roller, the scraper and the transfer roller, and stops on the carriage at the ends thereof to engage 130 and operate said toggle links. 120
7. In a machine of the character described, the combination of a frame, an ink roller, a transfer roller, a scraper between said rollers, a reciprocating carriage to carry a master board and a board to be printed successively beneath the ink roller, the scraper and the transfer roller, a master shaft, a rack on the carriage, a pinion on said shaft meshing with said rack, means for moving the transfer roller vertically into and out of operative position, and 135

a belt shifter operated coincident with the movement of said transfer roller.

8. In a machine of the character described, the combination of a main frame, an ink roller, a transfer roller, a 5 scraper between said rollers, a benzin tank supported on the main frame adjacent to the transfer roller, a benzin roller, a frame pivoted on the main frame to support said benzin roller in the tank or in engagement with the transfer roller, and a driven scraper roller to engage said transfer roller.

9. In a machine of the character described, the combination of a frame, an ink roller, a scraper, a transfer roller, 10

a revoluble shaft carrying said transfer roller and movable vertically to carry the transfer roller into and out of operative position, a sprocket wheel on said shaft, a roller arranged to operate in engagement with said transfer roller, a shaft 43 carrying said latter roller, a shaft 47 geared to said shaft 43, a sprocket wheel on said shaft 47, and a sprocket chain operating on said sprocket wheel. 15
